UNITED STATES PATENT OFFICE.

JOHN B. STEELE, OF BOONE, NORTH CAROLINA.

WIRE-STRETCHER CLAMP.

Application filed July 7, 1926. Serial No. 120,998.

This invention relates to wire stretchers and more particularly to a clamp by means of which one end portion of a woven wire fence fabric or the end portions of a series 5 of wires from which the fence is to be formed may be firmly gripped.

One object of the invention is to provide improved means for moving companion wire-engaging bars into gripping engagement with 10 fence wires disposed between the bars and firmly locking the wire-gripping bars.

Another object of the invention is to so form the clamps, by means of which the bars are moved into a gripping position that when 15 actuated to effect gripping of the wires the clamps will be prevented from accidentally slipping to a releasing position.

Another object of the invention is to mount the actuating levers of the clamps in housings which are secured to one of the bars and so constructed that they may be readily taken apart if it is found necessary to clean or repair the mechanism of the clamp.

This invention is illustrated in the accompanying drawing, wherein

Figure 1 is a view in side elevation illustrating the improved clamp applied to wire fencing of a conventional formation;

Fig. 2 is a longitudinal sectional view 30 through the clamp taken on the line 2—2 of Fig. 1;

Fig. 3 is a transverse sectional view taken on the line 3—3 of Fig. 2, and

Fig. 4 is a vertical sectional view taken on 35 the line 4—4 of Fig. 2.

The clamp forming the subject-matter of this invention includes companion bars 1 and 2 which are preferably formed of wood, although they may be metal and are of a 40 length corresponding to the customary height of woven wire fabric used when erecting fences. The fence wire 3 to be stretched is gripped for its full height between the bars 1 and 2 and, therefore, it will be evenly 45 stretched. In order to move the bars toward each other into firm gripping engagement with the wire fencing, there has been provided clamps which are indicated in general by the numeral 4 in Fig. 1 and illustrated in 50 detail in Figs. 2, 3 and 4. Two of the clamps have been employed but it will be understood that additional clamps may be provided if found necessary.

Each of the clamps is formed as shown in 55 Figs. 2, 3 and 4, and referring to these figures

it will be seen that each includes a pin 5 which passes through alined openings 6 and 7 formed in the bars 1 and 2 with its head 8 engaging the outer face of the bar 1. The portion of the pin which passes through the bar 1 is of greater diameter than its remaining portion and is threaded for engagement by the securing nut 9. It will be readily understood that when the securing nut is tightened the portion of the bar 1 between the nut and the head 8 will be firmly gripped and the pin will be held in engagement with the bar and prevented from turning. A recess 10 is formed in the inner face of the bar 1 about the opening 6 and is of sufficient depth to entirely receive the nut 9. Therefore, the nut 9 is countersunk in the bar 1 and cannot readily work loose upon the pin. This also prevents the nut from extending from the bar 1 and preventing the bar 2 from being moved into firm gripping engagement with the wire placed between the bars. The reduced portion of the pin extends well beyond the outer face of the bar 2 and has its free end portion formed with rack teeth 11 for engagement by actuating mechanism through the medium of which the bars are to be moved towards each other and held in gripping engagement with the fence wire.

The housing in which the actuating mechanism is mounted is secured to the outer face of the bar 2 about the opening 7 and is formed of separable side sections 12 and 13. These companion sections 12 and 13 are formed with base flanges 14 and 15 which are secured to the bar 2 by suitable fasteners, such as the screws 16, and at their upper ends are formed with flanges 17 and 18 releasably secured in contacting relation by the bolts 19. The main body of the housing is divided into an upper barrel 20 of a diameter to snugly receive the pin 5 and a lower compartment or chamber 21 by webs 22 and 23 which extend inwardly from the side sections, as shown in Fig. 4. These webs 22 and 23 are of less length than the barrel 20 and terminate in spaced relation to the bosses 24 and 25 through which the securing bolt 26 passes in order to provide a passage 27, as shown in Fig. 2. It should be further noted that the upper ends of the webs 23 are beveled, as shown at 28, to provide a cam surface for a purpose to be hereinafter brought out. Immediately below the bosses 24 and 25 the side sections 12 and 13 are recessed to pro-

vide a slot 29 and at their lower ends the side sections are provided with contacting lugs 30 and 31 through which are passed a securing bolt 32. By having the sections from which the housing is formed secured to each other by bolts and the housing secured to the bar 2 by screws or other removable fasteners, the housing may be readily removed from the bar and taken apart when necessary. Therefore, cleaning and repairing can be very easily accomplished.

The lever 33, by means of which the clamp is actuated, is in the form of an irregular curve and of a thickness to pass through the slot 29 and move freely in the slot. A head 34 is formed at the inner end of the lever and projects from opposite sides of the lever. This head is formed with an arcuate peripheral face which engages the washer 35, against which the outer end of the spring 36 bears and at the opposite side of the head from the lever there has been formed bearing ears 37, between which a pawl 38 is pivotally mounted upon a pin 39. This pawl is engaged by a leaf spring 40 anchored upon the bolt 26 and is urged towards the barrel 20 so that it will be forced through the slot 27 for engagement with the rack teeth 11.

When the clamp is in use, the levers 33 are swung outwardly to the dotted line position of Fig. 2 and when so swung the pawls are moved into the chambers 21 with their end portions engaging the inclined cam surfaces 28 and held out of engagement with the rack teeth. The bars may then be moved away from each other and entirely separated if so desired. If separate strands of wire are to be stretched, the bars will only be separated a sufficient distance to permit the wires to be passed between the bars but if the fence is formed of woven fabric the bar 2 will be entirely separated from the bar 1 and the wire placed in engagement with the inner face of the bar 1 and the bar 2 then replaced. The bar 2 rests upon the fence wires and when the levers are swung towards the position shown in Fig. 2, the pawls are moved through the slots 27 by their cooperating springs 40 and engage the rack teeth 11. The pawls will, therefore, act upon the pins 5 and when the levers are completely swung to the position shown in Fig. 2, the bars 1 and 2 will have firm gripping engagement with the fence wires. The head 34 is not only rotated in the chamber of the housing when the lever is swung towards the position shown in Fig. 2, but will also be slid bodily towards the bar a short distance and move the disk 35 away from the abutment shoulders 41 so that the spring 36 is compressed and pressure applied to prevent accidental movement of the lever towards the releasing position. Since it requires a rotary movement of the heads 34 in order to release the pins 5 from the pawls, the bars will be securely held in the clamping

position and there will be no danger of them accidentally slipping. After the fence wire has been firmly gripped between the bars of the clamp, a stretching tackle, indicated in general by the numeral 42, is attached, as shown in Fig. 1, and the fence wires may be stretched as tight as desired and firmly nailed to the fence posts while stretched. The fence wires will, therefore, all be evenly stretched by a single stretching operation.

Having thus described the invention, I claim:

1. A wire clamp comprising companion sections, a pin rigidly carried by one section and passed through an opening in the other section to slidably connect the sections, said pin being provided with longitudinally extending rack teeth, a housing secured against the outer face of the second section and formed with a barrel slidably receiving said pin and a chamber adjacent said barrel communicating therewith, said chamber having a slot formed in its wall, a lever extending into said chamber through said slot, a head at the inner end of said lever formed with an arcuate peripheral face and rotated in the chamber when the lever is moved, a pawl pivotally connected with said head, a spring in said chamber engaging said pawl to move the pawl into engagement with the rack teeth of said pin when the head is rotated in one direction, and spring means in said chamber bearing against said head to frictionally resist rotation thereof.

2. A wire clamp comprising companion sections, a pin rigidly carried by one section and passed through an opening in the other section to slidably connect the sections, said pin being provided with longitudinally extending rack teeth, a housing secured against the outer face of the second section and formed with a barrel slidably receiving said pin and a chamber adjacent said barrel communicating therewith, a lever extending into said chamber, a head at the inner end of said lever adapted to rotate in the chamber when the lever is moved, a pawl pivoted to said head, and a spring in said chamber engaging said pawl to move the pawl into engagement with the rack teeth of said pin.

3. A wire clamp comprising companion sections, a pin extending from one section through an opening in the other section to slidably connect the sections, said pin being provided with longitudinally extending rack teeth, a housing carried by the second section and formed with a barrel aligned with the opening of the section to slidably receive said pin and a chamber communicating with said barrel through one side thereof and having an outer wall formed with a longitudinally extending slot, a lever extending into said chamber through said slot, a head at the inner end of said lever rotatable in said chamber, a pawl pivoted to said head, a spring

engaging said pawl to yieldably hold the pawl in position for engagement with said rack teeth, a disk in said chamber, and a spring between said disk and one end of the chamber to retain said disk in engagement with said head and frictionally resist rotation of the head in the chamber.

5. A wire clamp comprising companion sections, a pin extending from one section through an opening in the other section to slidably connect the sections, said pin being provided with longitudinally extending rack teeth, a housing carried by the second section and formed of separable side sections having inwardly extending webs contacting to form a partition dividing the housing into a barrel to receive said pin and a chamber, said partition terminating in an end edge spaced from one end of said chamber to form a passage between the barrel and chamber, a head rotatable in said chamber, a pawl pivoted to said head and yieldingly held in position for engaging said rack teeth, and means for rotating said head to move the pawl inwardly of the chamber to an inoperative position with the beveled edge of said partition holding the pawl out of engagement with the rack teeth.

6. A wire clamp comprising companion sections, a pin extending from one section through an opening in the other section to slidably connect the sections, said pin being provided with longitudinally extending rack teeth, a housing carried by the second section and formed of separable side sections having inwardly extending webs contacting to form

a partition dividing the housing into a barrel to receive said pin and a chamber, said partition terminating in an end edge spaced from one end of said chamber to form a passage between the barrel and chamber, fasteners to releasably hold said side sections assembled, one fastener passing through said chamber, a head rotatable in said chamber, a pawl pivoted to said head, a spring carried by said fastener and engaging said pawl to yieldably hold the pawl in position for engagement with said rack teeth, and means for rotating said head to move the pawl into and out of engagement with said rack teeth.

7. A wire clamp comprising companion sections, a pin extending from one section through an opening in the other section to slidably connect the sections, said pin being provided with longitudinally extending rack teeth, a housing carried by the second section and formed of separable side sections having inwardly extending webs contacting to form a partition dividing the housing into a barrel to receive said pin and a chamber, said partition terminating in an end edge spaced from one end of said chamber to form a passage between the barrel and chamber, and operating means movably mounted in said chamber and including a pawl adapted to be moved through the passage into and out of engagement with said rack teeth according to the direction in which said operating means is moved.

In testimony whereof I affix my signature

JOHN B. STEELE. [L.S.]
